UNITED STATES PATENT OFFICE.

JAMES T. FITZ GERALD, OF SOUTH PITTSBURG, TENNESSEE.

STOVE.

Application filed September 4, 1928. Serial No. 303,865.

The present invention relates to improvements in stoves, and has for an object to provide an improved heating and cooking stove in which an economy in heating is effected 5 and the products of combustion more completely burned.

Another object of the invention is to provide an improved conjoint damper control, whereby the oven heat is regulated and the 10 fire-box draft controlled to effect economies in the operation of the stove.

With the foregoing and other objects in view, the invention will be more fully described hereinafter, and will be more particularly pointed out in the claims appended hereto.

In the drawings, wherein like symbols refer to like or corresponding parts throughout the several views,

20 Figure 1 is a top plan view, with parts, broken away, showing an improved stove constructed according to the present invention.

Figure 2 is a front elevation of the same, 25 with parts broken away.

Figure 3 is a diagrammatic view showing the damper arrangement in a subsequent position to that shown in Figure 2.

Figure 4 is a plan view of the stove with 30 the top removed.

Figure 5 is a transverse section taken on the line 5—5 in Figure 2.

Figure 6 is a perspective view, with parts broken away, showing the perforated top construction.

Figure 7 is a fragmentary vertical section through one of the stove doors.

Figure 8 is a front perspective view, with parts broken away, of a canopy top forming 40 a modified optional equipment.

Figure 9 is a rear perspective view of the same, and

Figure 10 is a cross section through the same.

45 Referring more particularly to the drawings 8 designates the stove casing, which, in this instance is preferably provided with the insulating lining 9. At 10 is shown the oven door, at 11 the fire door and at 12 the ash door. A transverse partition 13 adjoining the fire-box and ash pit is provided with an opening 14 just below the fire-box, and provides in one end of the stove a down-take draft passage 15.

50 This passage communicates at its upper end with a chamber 16 located between the re-

movable stove top 17 and the interior heating top provided with the stove lids 18. These stove lids are carried in plates or sections 19. These sections are provided in any suitable number, three being shown in the drawings. Such sections are supported upon the shoulders 20 within the rectangular or other frame 21 forming the skeleton stove heating top.

60 The preheating chamber 16 is adapted to receive air from the space above the stove through the perforated cover slabs. These slabs comprise upper perforated plates 22 and lower insulating plates 23. The insulating plates are also perforated, the perforations being in staggered relation with respect to the perforations of the metal plates 22.

65 The upper plates may be provided with flanges 24 to encompass the edges of the insulating plates 23 and both plates may be secured together in spaced relation by the screws, bolts or other fastenings 25. The slabs so formed in any appropriate number, 70 such for instance as the three slabs shown, are supported upon the flange or shoulder 26 carried at the margin of the rectangular or other opening provided in the stove casing top to receive the same.

75 Above and to the rear of the oven, the stove is provided with a damper box having an offset wall 27, shown in Figure 5, formed with ports 28 behind which slides the damper 29 having the slots 30 to register with the 80 ports 28. The damper plate is appropriately guided and is swivelly coupled by a link 31 to a sleeve 32 fixed on the rod 33, which connects with the levers 34 and 35 extending to and coupled with the pivoted damper valves 90 36 and 37. These damper valves control the ports 38 and 39 at opposite ends of the stove heating top.

85 In operation, all air draft necessary for the operation of the stove must pass through 100 the perforations in the top plates 22 and 23. As this air draft must make contact with the top surface, edge area of perforations, and bottom surface of both the metal and insulating material, a maximum cooling effect is 105 thus obtained without detracting from stove operation. After the air has passed through the perforated top, it comes in contact with the heated cooking top 19 and is thus pre-heated before being passed through the fire-box 40 by way of the draft passage 15 and 110 opening 14. This feature of preheating the

air draft insures more perfect combustion of fuel and a subsequent saving of approximately fifty per cent. This feature also uses the heat that commonly is radiated into the kitchen for raising the temperature in the stove.

The damper arrangement permits the maximum air draft through the top at all stages of operation of the stove, thus insuring the top remaining at a very low temperature.

The top is of further use in drawing into the stove cooking fumes which, in a large number of cases are objectionable and which customarily are removed from the kitchen by hoods located over the stove and discharging into the outer atmosphere.

The perforated top sections may be removed either wholly or in any of the units required for the purpose of giving access to the cooking top for the placing of cooking vessels thereon, and also for heating of the kitchen during cold weather, should this be desired.

As shown in Figure 4 the shaft of the damper 39 is extended and provided with a handle 41 at the front of the stove for convenient operation of all of the dampers.

The dampers 36 and 37 are assembled in the stove at 90° angles to each other, as shown in Figure 2. When the damper 36 is open, both the dampers 37 and 29 are closed. This is the position shown in Figure 2. This requires all air draft passing through the perforated top to come in contact with the cooking top 19 and to pass along the chamber 16 to a down-take passage 15, through the fire-box 40 along upper stove flue 42 above the oven and down through the down-take stove flue 43 at the far side of the oven and into the lower stove flue 44 below the oven. This lower stove flue connects, as shown in Figure 5, through port 45 with the smoke or chimney pipe 46. This smoke or chimney pipe is also connected by a branch 47 with the chamber 48 behind the sliding damper 29. This operation permits oven temperature to be brought to proper point at the same time cooking top 19 is being raised to cooking temperature.

When damper 36 is in closed position the other two dampers are open. Air draft then flows to the right (viewing Figure 2), across the cooking top 19, passing through port 39 and to the left through top flue 42. This air being preheated from passing across the cooking top is mixed with heavy gases discharged from the fire-box and causes further combustion and additional generation of heat within the stove. The draft then escapes through the sliding damper 29 into the smoke pipe. Also when the dampers are in this position, all draft through the fire-box 40 is stopped, and with air draft passing through top flue 42 and escaping through damper 29,

an instant control is had on stove temperatures both for the cooking top and oven. These dampers maintain relative positions to each other at all stages of operation from full direct draft to full check and escape, and at the same time permit full draft through the perforated top sections regardless of what the position of the dampers might be. This amount of draft for cooling top is, therefore, only determined by the height of flue 75 to which smoke pipe is connected. Whenever flue is of sufficient height for satisfactory operation of stove, it will be satisfactory for top cooling.

Referring particularly to Figure 7, a new type of fire, ash and soot door is so constructed to have in its interior a concave receiving portion 50 and provided with a hinge which enables the door to be removed from the stove. This hinge consists of a shank 51 affixed to the door structure, preferably at the lower portion thereof and extending diagonally away from the plane of the door and having an up-turned terminal end 52 for interlocking with the stove casing in which is provided an opening 53 for the hinge of greater thickness than the hinge to permit of the requisite play.

Figure 7 shows the open position of the door, showing its use as a catch-all when coaling, or when removing ashes and soot. The door will protect the stove and kitchen floor and when the concave portion 50 is filled and needs to be dumped, the hinged structure permits of the dismemberment of the door from the stove.

This entire stove has been designed to permit construction in individual units, which greatly reduces the up-keep to users in both labor and material repairs as compared with stoves having steel bodies now commonly in use.

Referring more particularly to Figures 8, 9 and 10, a modified form of stove top is shown, which may be used instead of the previously described top, where cooking and warming dishes is desired. In this canopy top, 60 designates a rear wall, 61 and 62 the end walls and 63 the top or roof. A front wall is also provided having the doors 64 and 65. The doors 64, two or more in number, communicate with the warmer compartment in the upper portion of the canopy top above the horizontal partition 66. The rear wall 60 is provided with numerous perforations 67, as shown in Figure 9. The bottom of the device is open, as shown in Figure 10 to receive heat from the stove.

In use the top previously described is removed, and the canopy top put in place, as shown in Figure 10. All of the air necessary for the operation of the stove is received through the perforations 67. Access is had to either compartment through the doors 64 and 65, cooking vessels being placed in the

lower compartment and vessels to be heated in the upper compartment. When the vessels are introduced the doors are closed, which prohibits the escaping of the hot air into the kitchen. The operation of the stove with this attachment is as previously described.

It is obvious that various changes and modifications may be made in the details of construction and design of the above specifically described embodiment of this invention without departing from the spirit thereof, such changes and modifications being restricted only by the scope of the following claims.

15 5. What is claimed is:—

1. In a stove, a cooking top, a draft-inlet stove top above the cooking top, and dampers connected for conjoint operation for circulating the draft to the flue either through the

20 fire-box and about the stove oven or directly to the flue without passing through the fire-box or about the oven.

2. In a stove, an oven, a cooking top above the oven, a draft inlet above the top, and 25 conjointly-controlled dampers at opposite portions of the inlet for circulating the draft to the flue either through the fire-box and about the stove oven or without passing through the fire-box.

30 3. In a stove, an oven having flues thereabout, a fire-box, an air-preheating chamber, a down-take connecting with the fire-box and

chamber, a by-pass connecting with oven flues at opposite side from the fire-box, alternately opening and closing dampers for the down-take and by-pass, a damper between the fire-box and by-pass leading to the chimney, and a common operating means connected to all the dampers.

4. In a stove, an oven having flues thereabout, a fire-box, an air-preheating chamber, a down-take connecting with the fire-box and chamber, a by-pass connecting with oven flues at opposite side from the fire-box, alternately opening and closing dampers for the down-take and by-pass, a damper between the fire-box and by-pass leading to the chimney, and a common operating means connecting to all the dampers and so coupled as to close the by-pass and last-mentioned damper when the 45 down-take damper is open.

5. In a stove having an oven with surrounding flues, and a fire-box, a cooking top above the oven, a perforated insulated sectional removable stove top spaced above the 55 cooking top, a down-take from the top the fire-box, a by-pass from the top to the oven flues, dampers in the down-take and by-pass, a damper in the upper oven flue, and a common operating means for the dampers, said 60 oven flues being connected above and below to the chimney flue.
